(57) **CLAIM**

The ornamental design for an embedded fan for bed, as shown and described.

DESCRIPTION

FIG. 1 is a top, front and left side perspective view of an embedded fan for bed showing our new design;

FIG. 2 is a bottom, rear and right side perspective view thereof;

FIG. 3 is a bottom, front and left side perspective view thereof;

FIG. 4 is a top, rear and right side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof; and,

FIG. 11 is a perspective view showing the embedded fan for bed in a use state.

The broken lines in FIGS. 1-10 illustrate portions of the embedded fan for bed that form no part of the claimed design.

The broken lines in FIG. 11 illustrate portions of the embedded fan for bed and environmental subject matters that form no part of the claimed design.
